SUCTION NOZZLE

**Josef Friedrich Heuberger, Stockholm, Sweden,
assignor to Electrolux Corporation, Dover, Del.,
a corporation of Delaware**

**Application July 27, 1938, Serial No. 221,509
In Germany August 2, 1937**

3 Claims. (Cl. 285—21)

My invention relates to vacuum cleaners and more particularly to an improved suction nozzle for use in connection with a vacuum cleaning unit of the type wherein means are provided for detachably connecting the suction nozzle to a hollow rigid handle and a flexible hose.

With a nozzle of this type it is desirable to have the hollow handle extend therefrom at an angle of approximately 45° when the nozzle is being used for cleaning a floor. However, when it is desired to clean underneath low furniture, or to clean a surface which is above the level on which the operator is standing, it is preferable to have the handle extend substantially parallel to the floor or other surface being cleaned. Heretofore, this has been accomplished by connecting the handle to the nozzle by means of some type of pivoted or swivel connection. However, this entails a rather expensive construction and also gives rise to the possibility of leakage.

In accordance with the present invention the nozzle is provided with two or more intersecting bores, the center lines of which extend in the different directions in which it is desired to have the handle extend from the nozzle. Furthermore, the bores intersect in such a manner that, when the hollow handle is received in any one of them, the other bore or bores are closed.

Further objects and advantages of my invention will be apparent from the following description, considered in connection with the accompanying drawing, which forms a part of this specification, and of which—

Fig. 1 is a cross-sectional view of a nozzle in accordance with my invention; and

Fig. 2 is a rear view of the nozzle shown in Figure 1.

Referring to the drawing, reference character 10 designates a hollow body formed with a lower elongated inlet opening 11, which may be surrounded by brush bristles 12. A strip of rubber 13 may be provided around the body 10 and serve both as a bumper and as a means for supporting the bristles 12. The space within the body 10, to which the elongated inlet 11 opens, converges to a centrally located circular opening 14 in the upper face of the body 10.

Secured to the body by means of screws 15 is a hollow connection member 16. Member 16 is formed with two intersecting bores, one of which is bounded by a slightly conical surface 17, while the other is bounded by a similar conical surface 18. These two surfaces intersect along a line 19 which forms a portion of an ellipse.

A hollow rigid handle member 20 has one end

formed slightly conical and is adapted to be received within either of the bores. As shown in solid lines in Fig. 1, the handle is received in the bore which is bounded by the surface 17 and in this position extends at about 45° to the surface with which the nozzle is in contact. It will be seen that in this position the handle 20 completely blocks off the bore which is bounded by the surface 18. If it is desired to use the nozzle under low furniture or for any other use in which the handle should extend substantially parallel to the surface being cleaned, the handle is removed from the position shown in full lines and placed in the position shown in broken lines, where it engages the bore which is bounded by the surface 18. In this latter position it completely blocks off the other bore.

In order to provide a somewhat better bearing for the handle in the nozzle when it is inserted in the full line position, which is the position in which it is chiefly used, a supporting member 21 may be provided which engages the lower upper side of the handle. The surface 22 on the member 21 which contacts the handle is made slightly conical. As will be seen from the drawing the member 21 is further provided with a surface contacting the under side of the handle when it is inserted in the nozzle in the broken line position, thus forming an improved bearing for the handle in said position. The member 21 should be comparatively narrow so as not to interfere materially with the flow of air when the handle is in the broken line position.

It will thus be seen that I have provided a nozzle and handle which may have different relative angular positions without requiring the use of any pivoted joint. While I have shown one preferred embodiment in my invention this has been done for purposes of illustration only, and has not intended to limit its scope, which is to be determined by the appended claims viewed in the light of the prior art.

I claim:

1. In a suction nozzle, a hollow body formed with an inlet and a plurality of outlets, said outlets being in the form of mutually intersecting bores, and a conduit member having an open end and a solid side wall receivable in any of said bores, the relationship of the intersecting bores being such that when said conduit member is received in any bore the solid side wall thereof extends across the remainder of said bores to thereby close the latter.

2. In a suction nozzle, a hollow body formed with an inlet and two intersecting outlet pas-

sages, a conduit member receivable in either of said passages, the relationship of the passages being such that when said conduit member is received in either passage it blocks off flow through 5 the other passage, and a projection within said hollow member provided with a surface which is aligned with the interior surface of one of said passages so as to contact and support said conduit member when the latter is received in said 10 one of said passages.

3. In a suction nozzle, a hollow body formed with an inlet and two intersecting outlet passages,

a conduit member receivable in either of said passages, the relationship of the passages being such that when said conduit member is received in either passage it blocks off flow through the other passage, and a projection within said hollow member provided with surfaces which are aligned with the interior surfaces of the respective passages so as to contact and support said conduit member when the latter is received in either of said passages.

JOSEF FRIEDRICH HEUBERGER.
